United States Patent Office

Des. 218,308

Patented Aug. 11, 1970

218,308

ELECTRIC UNIT HEATER

Kurt B. Boehm, Lake Bluff, and Tadeusz S. Otocki, Chicago, Ill., assignors to ILG Industries Inc., Chicago, Ill., a corporation of Delaware

Filed Sept. 9, 1968, Ser. No. 13,453

Term of patent 14 years

Int. Cl. D23—03

U.S. Cl. D23—110

FIG.1

FIG.2

FIG.3

FIG.4

FIG. 1 is a front elevational view of a unit heater embodying our new design;

FIG. 2 is a side elevational view of the unit heater of FIG. 1;

FIG. 3 is a rear elevational view of the unit heater of FIG. 1; and

FIG. 4 is a top view of the unit heater as shown in FIG. 2.

The dominant features of our design reside in the portions shown in solid lines.

We claim:

The ornamental design for an electric unit heater, substantially as shown and described.
